UNITED STATES PATENT OFFICE.

JAMES BELLINGER McALLISTER, OF ST. JOHNSVILLE, NEW YORK.

DENTAL PLIERS.

1,214,197.

Specification of Letters Patent. Patented Jan. 30, 1917.

Original application filed September 20, 1915, Serial No. 51,570. Divided and this application filed June 3, 1916. Serial No. 101,467.

To all whom it may concern:

Be it known that I, JAMES BELLINGER McALLISTER, a citizen of the United States, and a resident of St. Johnsville, in the county of Montgomery and State of New York, have invented a new and Improved Dental Pliers, of which the following is a full, clear, and exact description.

This invention relates to pliers and particularly to dental pliers and is a divisional 10 application of my prior application Serial No. 51,570, filed September 20, 1915.

The object in view is to provide an improved arrangement for holding a cord or ligature while the pliers are being operated 15 so that a knot arranged in the ligature may be drawn between adjacent teeth for causing a separation thereof.

A still further object of the invention is 20 to provide improved retaining means for the ligature which may clamp the ligature at any point and hold the same under proper tension.

In the accompanying drawings: Figure 1 25 is a plan view of a pair of pliers embodying the invention. Fig. 2 is an edge view of the structure shown in Fig. 1, one of the clamping nuts being removed. Fig. 3 is a plan view of part of a jaw with several teeth arranged thereon together with a short section 30 of cord. Fig. 4 is a fragmentary edge view of a tooth together with a ligature provided with a knot and one end of a pair of pliers associated therewith illustrating how the 35 pliers may force the knot between adjacent teeth.

In operating on teeth, as for instance, in filling teeth, it is sometimes necessary to separate adjacent teeth to a greater or less extent in order that the operator may place 40 a filling on the side of one tooth adjacent the next tooth. Various separating means have been provided for forcing the teeth apart but by reason of a more or less sudden or quick forcing apart of the teeth great pain is produced. Also, when a cord 45 or ligature is used for forcing the teeth apart it is necessary for the operator to place the fingers of one hand in the mouth of the patient and where the tooth operated upon is toward the rear of the mouth this is very difficult.

The present invention is intended to present a structure which will allow a ligature 55 to be quickly and easily forced between any

adjacent teeth and also to draw a knot between the teeth without the operator placing his fingers in the patient's mouth.

Referring to the accompanying drawing by numerals, 1 and 2 indicate the handles of the pliers which merge into body portions 3 and 4, said body portions in turn merging into jaws 5 and 6. The jaws 5 and 6 are provided with openings in the extreme ends, preferably notches 7, as shown in Fig. 2, 60 whereby the cord or ligature 7' may be properly held in position. Arranged on the body 3 is a threaded post 8 having an enlarged roughened base 9, as shown in Fig. 2, the end of the ligature 7' being adapted to be 65 pinched against the roughened surface of 70 enlargement 9 by a thumb operated nut 10. The enlargement 9 may be formed integrally with the post 8 or if desired it may be arranged loosely in position and post 8 secured 75 in any suitable way to body 3, the essential 80 point being in providing a surface against which the ligature may be pinched which surface, if preferred, may be merely the surface of body 3 instead of member 9. On the body 4 a similar arrangement is provided 85 to that described in regard to body 3 whereby both ends of the ligature are held against movement and are adapted to be clamped at any point.

The arrangement of the ligature in the pliers as shown in Figs. 1 and 2 is such as to readily permit the operator to force the ligature between adjacent teeth. In case it is desired to spread the teeth to a considerable extent a larger ligature 11 is provided, 90 as shown in Fig. 3, which is connected with the cord 7' and drawn between the teeth, after which a knot 12 is produced manually and then the ends threaded through the 95 jaws 5 and 6 and secured by the clamping members heretofore described. After this has been done the handles 1 and 2 are brought together and jaws 5 and 6 spread, which will cause the knot 12 to move into a 100 position between the teeth. If the first movement for spreading the jaws does not accomplish this result some of the slack cord may be taken up and the jaws then again operated until the knot is at the proper 105 place. If one knot is not sufficient for producing the proper spreading of the teeth a second knot may be provided or, in fact, any number of knots may be used. By gradually increasing the amount of material 110

placed between the teeth a gradual even spreading is produced.

What I claim is:

In dental pliers of the character described,
5 a pair of handles merging into body portions which in turn merge into jaws, means for pivotally connecting said body portions together, each of said body portions being

provided with a serrated or roughened section, a threaded member extending from 10 said serrated or roughened section, and a thumb member mounted on said threaded member for gripping the end portions of a ligature, said jaws being adapted to carry said ligature.

JAMES BELLINGER MCALLISTER.
